UNITED STATES PATENT OFFICE.

JOHN A. HARTVIG, OF OAKLAND, CALIFORNIA.

WAVER FOR HAIR.

Application filed October 31, 1922. Serial No. 598,060.

To all whom it may concern:

Be it known that I, JOHN A. HARTVIG, a citizen of the United States of America, and resident of the city of Oakland, in Alameda County, State of California, have invented certain new and useful Improvements in Wavers for Hair, of which the following is a specification.

My invention relates to an improvement 10 in hair wavers of the type shown in my co-pending application Ser. No. 549,487.

My present invention has two important objects, the first being to adapt such a waver for use with bobbed hair, by making 15 it possible to grip the ends of the hair securely to permit it to be wound upon the waver. The second object is to provide means whereby the heated rod which is employed in connection with the waver may 20 be securely held in place therein without danger of its accidental removal or falling from the waver.

A further object is the provision of means for guiding the heated rod into the tube.

25 A further object is the provision of means for preventing the conduction of heat from the heated portion of the rod to its handle.

A further object is the general simplification and improvement of the structure of 30 such wavers and in general the improvement of their application to the work intended.

My invention comprises those novel parts 35 and combinations thereof which are shown in the accompanying drawings, described in the specification, and particularly defined by the claims terminating the same.

In the accompanying drawings I have 40 shown my invention in the form which is now preferred by me.

Figure 1 is a plan view of a portion of a person's head showing the manner of using the wavers.

Figure 2 is a longitudinal section through 45 the waver.

Figure 3 is an end elevation of the waver.

Figure 4 is an elevation of the heating rod.

Figure 5 is a perspective view of a slight 50 modification.

The waver comprises a spindle or tube 1 upon which the hair is wound, a bifurcated yoke, the arms 2 of which lie normally adjacent the tube 1 and which is pivoted to 55 the tube at the bend, as indicated at 21, a sleeve 3 which is supported upon the arms

2 of the yoke and which is adapted to embrace the free end of the tube to connect together the tube and yoke, and a poker or rod 4 which is intended to be heated and 60 then to be inserted within the free end of the tube 1. This much has been shown in my former application and forms no part of the present invention.

The arms 2 of the yoke are preferably 65 formed of somewhat resilient material, or at least the ends 24 thereof are resilient and preferably their tips are bent outwardly somewhat. The rod 4 is provided with a head 41, which in the form shown 70 herein is of wood, and forms a handle. With the yoke 2 and sleeve 3 in the relative positions shown in Figure 2, the rod 4 may be inserted within the end of the tube 1 until its head or handle 41 is engaged by 75 the tips 24 of the yoke arms. These frictionally engage the handle 41 and by their grip prevent its accidental removal. The relative position of these parts is shown clearly in Figure 3.

80 As the device is ordinarily used, with long hair, the tube 1 is laid adjacent the user's scalp and the hair wound thereon, the ends of the strands of hair being last wound about the tube. In this manner there is no 85 possibility of the hair slipping from the tube and as it is the hair nearest the scalp which it is desired to wave, this produces the best results, inasmuch as that portion of the hair nearest the scalp is inside, nearest 90 the poker or rod 4. With bobbed hair, however, it is the ends of the hair which must be most curled, and in order to prevent the ends of the hair from slipping about the tube 1 I have provided a clip 5, best 95 shown in Figure 1, which lies alongside the tube 1 and which is intended to receive and hold the ends of the hair between it and the tube 1. By inserting the ends of the bobbed hair between the clip 5 and the tube 1, and 100 then by winding it upon the tube, the ends of the hair are brought inside, nearest the heated rod, and are given the greatest curl. The clip 5 may be of any suitable material, and might be made in a variety of different 105 forms. I have shown it as formed of spring wire, free at one end and having its opposite end bent in U-shape as indicated at 51, and passed twice through the tube 1, although any other suitable means of holding the clip in place may be employed.

110 In using the device for long hair the clip

5 may be used or may be ignored, as may be desired. The hair is wound upon the tube 1, starting near the scalp, the yoke arms 2 are brought up to include the hair 5 wound upon the tube, and the sleeve 3 is slid along the arms 2 until it receives and holds the free end of the tube 1. It may be slid along the yoke until it squeezes the hair wound on the tube down towards the 10 opposite end thereof. The poker 4 is then heated and inserted, the ends 24 of the yoke holding it in place.

In connection with the rod 4 which is intended to be heated, it is my invention to 15 provide means whereby the conduction of heat from the heated portion to the handle may be lessened greatly. To this end I provide one or more flattened portions 42, preferably positioned adjacent the handle 20 41. Heat passing along the rod 4 will not pass so readily by the flattened portions. These will act in some degree as radiators, being of greater surface area than the rod.

The ends 24, being equally spaced from 25 an extension of the axis through the tube 1, and diametrically opposite each other, serve as a visual guide to assist in inserting the rod 4 into the tube. If a more positive guide is desired, these ends might be broadened, or the sleeve 3 may be formed with flared wing extensions 31, these serving somewhat as a funnel to guide the rod into the end of the tube 1. Any suitable guide may be employed, but it has been found that 35 the visual guide provided by the ends 24 is both effective and simple, and does not add to the cost of the article.

What I claim as my invention is:

1. A hair waver comprising a tube, a yoke 40 pivotally secured to one end thereof, means for connecting together the free ends of the yoke and tube, a rod insertible within the free end of the tube, and means associated with the free end of said yoke for engaging the rod when inserted to prevent its accidental removal.

2. A hair waver comprising a tube, a yoke pivotally secured to one end thereof, means for connecting together the free ends of the yoke and the tube, a rod insertible within the free end of the tube and having an enlarged handle, said yoke having resilient tips upon its free end frictionally engageable with said handle to prevent accidental removal of the rod.

3. A hair waver comprising a tube, a yoke 60 of resilient material carried thereby, a heating member that detachably enters the tube and is adapted to be engaged by the yoke, and a sleeve slidably mounted on the tube and yoke and frictionally held by the resiliency of the latter at different points along the tube, said sleeve performing the double function of holding the hair wrapped 65 around said tube and also holding the yoke

in engagement with the heating element to maintain the latter in the tube.

4. A hair waver comprising a tube, a yoke pivotally mounted on one end of the tube and having permanently bowed side arms 70 of resilient material that extend beyond the opposite end of the tube, a heating member that detachably enters the tube and projects from the end beyond which the side arms extend, and a sleeve element slidably mounted on the arms and movable thereon beyond the end of the tube and to a position to engage the tube, said sleeve element serving to move said arms towards each other and into holding engagement with the projecting end of the heating element.

5. A hair waver, comprising a tube, a yoke pivotally mounted on one end of the tube and having permanently bowed side arms that extend beyond the opposite end 80 of the tube and are of resilient material, a sleeve element slidable on the side arms to different points along the tube and to a point beyond the tube, and means for preventing the detachment of the sleeve element 90 from the free ends of the side arms and also from the pivoted end of the yoke, said sleeve element serving to move the side arms laterally when slid along the latter.

6. A hair waver comprising a tube, a bifurcated yoke of resilient material pivotally secured to one end thereof at the bend of the yoke, a sleeve slidable upon the arms of said yoke and adapted to embrace the free end of the tube, the arms of the yoke being 100 normally bowed relative to the tube, a rod insertible within the free end of the tube, and having an enlarged head, said head being frictionally engageable by the ends of the yoke arms to prevent accidental removal 105 of the rod, and the pressure of the yoke arms upon the head being regulable by movement of the sleeve along the yoke.

7. A hair waver, comprising a tube, a yoke pivoted to one end of the tube, means 110 engaging the other end of the tube and the yoke for holding the latter against pivotal movement, a heating element that is detachably mounted on the tube, and a hair holding clip on the tube and secured thereto adjacent to the pivot mounting of the yoke.

8. A hair waver, comprising a tube that is open at both ends and will permit the free circulation of air therethrough, a hair holding yoke pivoted on one end of the tube, 120 means at the other end of the tube for holding the tube and yoke against relative pivotal movement, and a heating rod insertible into one of the open ends of the tube and having thin lateral projections that serve 125 to space the main portion of the rod from the tube and permit the passage of air around the rod.

9. A hair waver, comprising a tube that is open at both ends and will permit the free 130

circulation of air therethrough, a hair holding yoke pivoted on one end of the tube, means at the other end of the tube for holding the tube and yoke against relative pivotal movement, and a heating rod insertible into one of the open ends of the tube and having a handle at one end, said rod having a reduced portion adjacent to the handle that prevent the passage of heat from the main portion of said rod to the handle. 10

Signed at Oakland, Alameda County, California, this 16th day of October, 1922.

JOHN A. HARTVIG.
